UNITED STATES PATENT OFFICE.

WELCH BARSTOW, OF SPOKANE, WASHINGTON, ASSIGNOR TO THOMAS F. RYAN, OF SPOKANE, WASHINGTON.

METHOD AND COMBUSTION APPARATUS.

Application filed December 27, 1920. Serial No. 433,369.

To all whom it may concern:

Be it known that I, WELCH BARSTOW, a citizen of the United States, residing at Spokane, in the county of Spokane and 55 State of Washington, have invented new and useful Improvements in Methods and Combustion Apparatus, of which the following is a specification.

This invention relates to improvements in 10 heaters which are especially adapted for use in fruit cars where it is desired to maintain a temperature constantly above a predetermined low temperature, and a temperature otherwise as uniform as possible.

15 In view of the fact that these cars are tightly closed in cold weather there is no air ingress thereto except by leakage, and therefore, a heater dependent upon any relative extent of natural or other draft is im-

20 practicable. Furthermore, the contents of these cars are highly sensitive to impurities in the air and consequently such a heater must be smokeless and odorless in addition to being capable of operating without draft.

25 It is an object of this invention to provide a heater which can be initially charged at the beginning of a trip to burn continuously for twenty-four hours, the heater being recharged each day of the trip. To compensate for different degrees of temperature, I 30 preferably employ a greater or less number of heaters for each car.

Owing to the fact that maintenance and 35 return shipment of heaters involves a great deal of expense, it is a feature of this invention to provide a heater of such economical construction that it can be discarded at the end of a trip.

In accordance with the preferred form of 40 my invention, the heater is in the form of a receptacle which is adapted to be filled with a loose bulk fuel to the height limit of its containing capacity, the heater having means for varying combustion supporting 45 air ingress thereto in accordance with the varying conditions incident to a lowering level of the burning zone, the fuel burning downwardly from the top. In this connection, it may be stated that I prefer to employ a novel form of fuel which constitutes a 50 separate invention and which will subse-

quently be disclosed in another application in which proper cross reference will be made to this case, and vice versa. Some of the main characteristics of this fuel are that instead of flaming during combustion, it merely glows, and further, instead of lending itself to a rapid combustion it, on the contrary, is slow combustible fuel.

Now therefore, as the container is filled 60 full with this fuel, and with the same burning downwardly from the top, the accumulating ash, and its blanket action requires not only a different and varying control of air ingress as the burning zone descends to 65 successively lower elevations, but this control of air ingress is so arranged as to provide for a substantially uniform rate of combustion so that a charged heater will burn for a predetermined period of time. 70

In this connection, my invention not only relates to the apparatus, but also to the method whereby these novel functions are performed.

It is a feature of my invention to provide 75 an effective heat insulation for the purpose of reducing fire danger to a minimum, and in accordance with my invention, the heater body is attached to a base, between which and the heater body, is interposed a heat insulating material, it being a special feature of my invention to employ lime as such material.

In order to simplify and facilitate the 85 labor of carrying the heater by hand, the same is provided with a bail and the latter is pivoted off-center to the heater so that gravity will act to tilt the heater, or the lower end thereof, away from the legs of the carrier to permit the latter to freely 90 walk without interference.

A further feature of novelty consists in a lid for the heater which is so co-actively associated with the bail that when the lid is lifted for filling purposes, it will not only 95 be supported by the bail in its elevated position, but it will additionally seek to tilt itself by gravity out of obstructing relation to the open top of the heater thereby greatly facilitating the charging operation thereof. 100

Other features of novelty will be more fully described in connection with the ac-

companying drawings and will be more particularly pointed out in and by the appended claims.

In the drawings—

5 Figure 1 is a view in elevation of my improved heater.

Figure 2 is a similar view with the greater portion of the structure broken away and shown in section.

10 Figure 3 is a view showing the lid elevated and tilted to permit of filling or charging the heater.

Figure 4 is a view in side elevation showing the lid tilted.

15 Like characters of reference designate similar parts throughout the different figures of the drawings.

20 My improved heater includes a base which may be of sheet metal and which is shown as having a supporting flange adapted to rest upon the floor. The base includes an upright portion 2 provided with a plurality of openings 3 for free ingress of air. The top of the base has a flat marginal portion 4, extending about the periphery, the central portion 5 being concave or depressed radially inwardly from the marginal flange 4 to provide a cavity of some considerable cubic contents.

25 30 In the preferred form of my invention, I utilize this cavity for holding a heat insulating material preferably of bulk and powdery form. It is a special feature of my invention to employ lime, as indicated at 6, lime being not only one of the most effective nonconductors of heat but also one of the most economical. This latter factor is especially important in the construction of a heater which is to be discarded at the termination of each usage or trip.

35 40 My improved heater body is superimposed upon the base and includes, as an element thereof, a cylindrical guard 7 having an imperforate bottom 8 which extends abreast of the top of the depressed or concave portion 5 and abuts against the flat marginal flange 4. As will presently appear, the heater is permanently secured to the base, and this 45 feature enables me to effectively close the concave portion 5 in order to retain the lime therein. It will be noted that the upright wall of the guard is imperforate and is also corrugated thereby enabling me to 50 obtain rigidity and strength with a very 55 light gauge metal.

50 60 Inside of the guard 7, and superimposed upon the bottom 8, thereof, is the fuel container 9, which like the guard and base is cylindrical in form. The fuel container 9 is of reduced diameter with respect to the guard 7 to provide an annular intervening space 10 therebetween, the function and purpose of which will be hereinafter set forth 65 and developed. The lower margin 11, of

the container 9, is bent outwardly to form a flange, as is clearly shown in Figure 2. A perforate fuel supporting false bottom 12, is provided for the container 9, and this false bottom is slightly elevated with respect 70 to the bottom 8, to provide an insulating air space which functions as such notwithstanding the fact that circulation of air is permitted therein, the same being not dead air space. The false bottom 12 extends downwardly at 13 in abutting relation with the retainer wall 9, and thence outwardly at 14, under the flange 11 and over the same as at 15. Rivets 16 extend through these lapped thicknesses, and 75 through the base, to unite the parts as clearly shown in Figure 2. Of course this conventional construction or fabrication may be varied within the skill of a sheet metal worker without departing from the spirit 80 of the invention.

85 Before entering into further description of the main features of the heater body, I will next describe certain novel features of lid and bail construction.

90 A lid or cover is provided for the container 9, of said heater body, said cover having a flange 17 fitting about the container 9, the flange 17 has a top 18 to which is secured a screen 19 whereby the top of the heater will be free to the air for passage of the latter into the top to support combustion and for ascent of the heated air through said screen after the manner of a register. A carrying bail is pivoted at 20, to the container 9, at a point below the flange 17, and limb sections 21 extend upwardly through the top 18 of the cover in converging relation, as clearly shown in Figure 1. The bail is 95 of resilient metal and the apertures 22 are 100 only slightly enlarged with respect to the cross section of the bail wire sufficiently to permit the lid to slide upwardly and tilt on the bail. At 23, the limbs of the bail are 105 off-set in diverging relation and from these offset portions the bail is gently arched at 24 to provide a convenient grip or handle. Now as the cover is elevated along the bail, the sections 21 will be spread until the 110 apertures 22 reach the diverging portions 23, 115 whereupon the spreading tension on the bail will be released and the bail will quickly 120 spring or contract to dispose the diverging sections 23 in the apertures 22 thereby supporting the lid upon the bail at an elevation 120 above the container.

125 The purpose of this construction of supporting the lid at an elevation is to facilitate filling the container and I will next describe an additional feature whereby when the lid is thus supported, it will automatically seek to tilt itself by gravity out of obstructing relation to the open top of the container 9.

130 By reference to Figure 4, it will be noted

that the pivotal connection 20, of the bail, is off center with respect to a vertical line 25 parallel with the axis of the container. Furthermore, the apertures 22 are off center 5 and consequently a greater weight A of the lid is on one side of the bail. Thus the lid will seek to assume the position shown in Figure 4, which is nearly vertical, thereby leaving the top of the container 9 free and 10 unobstructed.

Reference will next be made to further features of construction of the heater body and to the functions performed thereby.

The fuel supporting bottom 12 is of per- 15 forate construction, as will be seen by reference to Figure 2. Air openings 26 permit of air ingress through space 10 to the bottom of the fuel body or mass 27. Furthermore, the container 9 has alternately disposed per- 20 forate and imperforate sections 28 and 29 extending upwardly from the bottom there- of. The guard 7 projects slightly above the perforate sections 28, the reason being to prevent sparks from shooting outwardly 25 and forming a fire menace. This is one function of the guard 7. Above the per- forate sections 28, the container 9 is con- tinuously imperforate thereby forming an upper stack section B.

30 In operation, the container will first be filled with fuel 27 to the height of its containing capacity. While this fuel is of a finely comminuted character, it also has fibrous ingredients which will prevent ob- 35 jective discharge through the perforate portions of the heater. The mass of fuel is ignited from the top and initially, com- bustion supporting air will find ingress through the perforate cover, whereas the 40 heated air will rise or ascend through said cover. If the car is in motion, the jolts and jars will of course tend to pack the fuel but because of the dry nature thereof, these same jolts and jars will also tend to con- 45 tinuously displace the fuel particles and loosen the upper portions thereof near the burning zone so that the one defective action will be counter-balanced and offset by the effective action. However, irrespective of 50 any packing action that may result, very little combustion supporting air will reach the burning zone while the same is above the perforate sections 28, or in other words, be- 55 fore the burning zone descends below the stack section. When combustion is started, there will be very little ash. As combus- 60 tion proceeds and the burning zone descends, a blanket of ash will form and of course this ash will have a blanket action tending to re- 65 tard combustion as it will tend to gradu- ally close off air ingress through the top as the ash increases in thickness. I have care- fully calculated the size of the container with the action of this burning fuel and find 70 that an imperforate upper section of the

depth shown, together with the accumulat- ing ash, will control and prolong combus- tion thereby preventing a too rapid con- sumption of fuel.

This is the first burning stage or zone. 70 After the burning zone descends to the up- permost openings of the perforate sections 28, then there will be a certain air ingress to support combustion for a further stage and which will off-set the retarding action 75 of the relatively thick blanket of ash. The alternately disposed perforate and imper- forate sections are calculated and propor- tioned to limit air ingress at this stage of combustion so that the rate of combustion 80 will not only be uniform but at substantially the same rate as in the stack section. Now the ash produced from this fuel is of a very fine and powdery nature and therefore its in- creasing thickness will not prevent the upper 85 imperforate section B from performing the function of a stack. Prior to descent of the burning zone below the stack, the air passes downwardly through the top and ash then upwardly, thereby passing twice through 90 the ash. Thus there is a progressive de- crease of air applied to the mass while in the stack to that elevation where combustion would be retarded if air were not admitted through sections 28. Hence the air entering 95 the perforate sections 28 will be drawn ra- dially inwardly to support combustion near the center of the mass. If the perforate sec- tions were not in any way restricted, they would, in combination with the stack action, 100 initiate a too rapid rate of combustion of the fuel hence the guard 7. This guard 7 functions to render air ingress to the sec- tions 28 gradually less effective as the burn- ing zone descends. In other words, the 105 further downwardly the burning zone de- scends, the more restricted will be the path of the air as it must follow over the top edge and descend into the space 10. Fur- thermore, by reason of the air in the space 110 10 being heated, it will seek to ascend and therefore combustion supporting air ingress will thus be gradually restricted with a view of retarding the rate of combustion to a sub- stantially uniform rate. This may be termed 115 the second burning stage or stage control.

As the burning zone descends to about one-third of the height of the perforated sections 28, then the mass above the fuel supporting bottom 12 will have been re- 120 duced sufficiently so that air ingress may be taken through the opening 26 and up- wardly into the mass through the openings of the false bottom 12. This materially in- creases the air ingress supply, or rather the 125 means for affording entrance of such air up through the fuel. However, such supply will likewise be restricted by the height of the guard 7 to the end that throughout the combustion process there is a complete and 130

automatic control functioning to not only render the rate of combustion uniform, but also to prolong combustion for a predetermined period.

- 5 It will be clear that in burning a mass of fuel of this character from the top downwardly, a very distinct problem is involved in controlling entrance of combustion supporting air as the burning zone descends, 10 the blanket action of the ash varying in its retarding action in proportion to its depth. Furthermore, the means for automatically controlling the air does not necessitate movable parts nor thermostatically controlled 15 parts.

It will also be noted that irrespective of the particular apparatus employed, my invention resides in the method of confining a body of fuel burning downwardly from 20 the top and automatically varying and controlling air ingress thereto under varying conditions incident to descent of the burning zone.

It is believed that the method and apparatus of my invention will be fully understood from the foregoing description and while I have herein shown specific forms 25 of the invention, I do not wish to be limited except for such limitations as the claims 30 may import.

I claim:-

1. In a heater of the class described, a base having an imperforate top with a flat marginal rim and the central portion of 35 said top being concave, a heater body having a flat imperforate bottom secured to the rim of said base and forming with said concave portion a closed cavity, a heat insulating material filling said cavity, said heater 40 body having a fuel supporting perforate false bottom elevated with respect to said imperforate bottom to provide an insulating air space.

2. In a heater of the class described, a 45 heater body having a fuel supporting bottom, a housing rising from said bottom and forming therewith a container for the fuel, a lid closing the top of said housing, and a guard surrounding said housing in spaced 50 relation thereto.

3. In a heater of the class described, a heater body having a fuel supporting bottom, a housing rising from said bottom and forming with said bottom a receptacle for 55 the fuel, and said housing being of perforate material for a lower portion of its height and being imperforate at its upper portion, a perforate lid covering said housing, and an imperforate guard surrounding 60 said housing in spaced relation thereto and extending upwardly from the bottom to a level approximately above the perforate portion of said housing.

4. In a heater of the class described, a 65 heater body having a fuel supporting bot-

tom, a housing rising from said bottom and forming therewith a receptacle for the fuel, and said housing being perforate for a lower portion of its height and being imperforate at its upper portion, and a perforate lid 70 closing the top of said housing.

5. In a heater of the class described, a base having a top, a heater body having a bottom seated on said top, and said heater having a perforate fuel supporting false 75 bottom elevated with respect to the aforesaid bottom of said heater to provide air ingress to the bottom of the fuel body.

6. In a smokeless and odorless heater, a heater body adapted to contain fuel to the 80 height limit of its containing capacity with the fuel burning downwardly from the top, the top of said heater being open, and the wall of said heater body having alternate perforate and imperforate areas arranged 85 with respect to the height of said body to control and support combustion substantially uniformly as the burning zone descends and compensating for the cumulative blanket action of the superimposed ash. 90

7. In a smokeless and odorless heater, a heater body adapted to contain fuel to the height limit of its containing capacity for uniform burning for a predetermined period, and said heater body having means 95 for controlling and supporting combustion under varying conditions incident to descent of the burning zone in said heater body.

8. In a smokeless and odorless heater, a 100 heater body adapted to contain fuel to the height limit of its containing capacity with the fuel burning downwardly from the top, said body having a perforate portion extending upwardly from the bottom of said 105 heater, and a retarding guard extending upwardly in spaced relation alongside of said perforate portion for rendering the latter gradually less effective to air ingress as the burning zone descends for controlling and 110 prolonging combustion to a predetermined period.

9. In a smokeless and odorless heater, a heater body adapted to be filled with fuel with the fuel burning downwardly from the 115 top, said body having alternately arranged perforate and imperforate portions extending upwardly from the bottom of said heater, and an imperforate retarding guard extending upwardly alongside of said perforate and imperforate portions for rendering said perforate portions gradually less effective to air ingress as the burning zone descends for controlling the rate of combustion. 120

10. In a smokeless and odorless heater, a heater body adapted to be filled with fuel with the fuel burning downwardly from the top, said body having a perforate portion extending upwardly from the bottom there- 125 130

of, an imperforate retarding guard extending upwardly alongside of said perforate portion for rendering said perforate portion gradually less effective to air ingress 5 through said portion as the burning zone descends, and a stack section above said perforate section, for inducing inflow of combustion supporting air.

11. In a smokeless and odorless heater, a 10 heater body adapted to be filled with fuel, with the fuel burning downwardly from the top, said body having a perforate portion extending upwardly from the bottom of said heater, an imperforate retarding guard extending 15 upwardly alongside of said perforate portion for rendering the latter gradually less effective to air ingress through said perforate portion as the burning zone descends, said heater having a stack section above 20 said guard and perforate portion, and the top of said heater being open.

12. In a smokeless and odorless heater, a 25 hollow heater body adapted to be filled with fuel with the fuel burning downwardly from the top, said body having a perforate

portion extending upwardly from the bottom of said heater, an imperforate retarding guard extending upwardly alongside of said perforate portion for rendering the latter gradually less effective to air ingress 30 through said perforate portion as the burning zone descends, and said guard being in spaced relation to said perforate portion, the bottom of said body being perforate and opening to the space between said guard 35 and perforate portion for supply of air.

13. The herein-described method of fuel combustion to cause a body of fuel to burn from the top downwardly for a predetermined period, which consists, in igniting the 40 body of fuel at the top thereof, in closing air ingress to the sides of said body from the top downwardly for a portion of the height of said body, and in regulating the rate of air admission to lower portions of said body 45 according to the progress of downward combustion.

In testimony that I claim the foregoing as my own, I hereby affix my signature.

WELCH BARSTOW.
